Fig. 6

Fig. 7

Fig. 8

FIG. 1 is an elevational view of the house side of a street lighting electric light bulb embodying our new design.

FIG. 2 is an elevational view of the street side of the street lighting electric light bulb.

FIG. 3 and 4 are end elevational views thereof.

FIG. 5 is a top plan view thereof.

FIG. 6 is a bottom plan view thereof.

FIG. 7 is an enlarged sectional view taken on line 7-7 of FIG. 5.

FIG. 8 is an enlarged sectional view taken on line 8-8 of FIG. 5.

We claim:

The ornamental design for a street lighting electric light bulb, as shown and described.
